UNITED STATES PATENT OFFICE

2,570,250

TUNNEL FREEZER

Herman W. Kleist, Chicago, Ill., assignor to Dole
Refrigerating Company, Chicago, Ill., a corpo-
ration of Illinois

Application October 20, 1948, Serial No. 55,447

5 Claims. (Cl. 62—102)

1

My invention relates to an improvement in refrigerating devices, and has for one purpose to provide a unit for freezing articles such, for example, as food.

Another purpose is to provide a material freezing unit in which the articles to be frozen are subjected to sub-zero temperatures and are reduced to sub-zero temperatures in a relatively short time.

Another purpose is to provide a method for quick-freezing articles of food.

Another purpose is to provide a cabinet assembly which may be readily shipped.

Another purpose is to provide a quick-freezing cabinet assembly which may be shipped in relatively small sub-units, when it is desired to have a completed unit of greater size and length than lends itself to easy packing and shipment.

Other purposes will appear from time to time in the course of the specification and claims.

I illustrate the invention more or less diagrammatically in the attached drawings wherein:

Figure 1 is an end elevation with the door open;

Figure 2 is a section on the line 2—2 of Figure 1;

Figure 3 is a section on the line 3—3 of Figure 2;

Figure 4 is a perspective view of the opposite end of the unit;

Figure 5 is a section, on an enlarged scale, on the line 5—5 of Figure 2;

Figure 6 is a cycle diagram;

Figure 7 is a perspective view of a composite unit; and

Figure 8 is a longitudinal section through the composite unit of Figure 7.

Like parts are indicated by like symbols throughout the specification and drawings.

Referring to the drawings, I generally indicate any suitable supporting surface, such as the floor of a room. A generally indicates an insulated housing having, for example, an insulated bottom wall 2, an insulated top wall 3, and insulated side walls 4 and 5. The details of the insulation do not, of themselves, form part of the present invention, and any suitable insulated cabinet structure may be used. As will be clear from Figures 1 and 2, I illustrate a cabinet which has an opening or interior 6 extending from end to end therethrough, the ends of the opening being closed by any suitable insulated doors 7 and 8 which may be suitably supported, for example, upon hinges 9. In effect, I therefore provide a tunnel of uniform cross-sectional area from end to end, as shown in Figure 7, with any suitable

2

securing means 10 being employed. When two such units are secured together any suitable gasket may be employed upon or between the abutting ends of adjacent units.

5 The interior of the housing is divided into a plurality of parallel passages by shelves in the form of freezing plates. Referring, for example, to Figures 5 and 6, I illustrate a plurality of plates, each of which is shown as having an upper sheet metal member 15, a lower sheet metal member 16, and a circumferential connecting flange 17, the parts being welded or otherwise secured to provide a substantially gas-proof element. Within the interior of the plate or shelf 15 thus formed I employ cooling coils 18 through which any suitable volatile refrigerant may be circulated. The top plate members or sheets 15 may have upwardly extending side flanges 19. It will be understood that I may employ any suitable securing means for supporting a plurality of the shelves in vertically superposed relationship within the cabinet or housing, as shown in Figure 4. The plates may, if desired, be made removable, and are shown as resting on any securing abutments 20.

I find it advantageous to cycle a volatile refrigerant through the plates in a pair of separate groups, but it will be understood that any suitable arrangement may be employed for admitting a volatile refrigerant for evaporation within the coils 18 of the individual plates. I illustrate, for example, a motor 25 driving any suitable compressor 26 from which compressed refrigerant is delivered to any suitable condenser 27 and receiver 28. 29 is a high pressure liquid duct with a branch 30. 31, 32 indicate any suitable pressure reduction means. 33, 34 indicate the low pressure refrigerant supply ducts extending to specific plates 35, 36. 37 indicates any suitable connecting passages to connect the plates in groups, and 38, 39 are return pipes which join at 40 and return to the compressor 26. Whereas this constitutes a satisfactory cycling arrangement, I do not wish to be specifically limited thereto. I may, if I wish, provide a less than atmospheric pressure within the plates. Thus the plates may be partially evacuated through any suitable valving and sealing means 50, as shown in Figure 3. Thus the walls 15 and 16 are thereafter held by atmospheric pressure in proper heat exchange relationship with the evaporator coils 18. I may also provide an eutectic within the plates if I wish, such an eutectic being shown at 51 in Figure 5. It will be understood that the eutectic, frozen by the

evaporation of volatile refrigerant within the coils 18, serves as a cold storage means.

I provide on one of the doors 8, one or more fans or air circulating devices 60, which may be suitably connected to any suitable source of electricity. Each fan 60 will deliver air along the aligned passages 60a, the air so delivered recirculating through the passages 60b, which are out of alignment with either fan. It will be understood that, if a plurality of housing units are employed, as in Figure 7, it may be desirable to have fans on each door, or to have the plates or shelves of the two units abut at their opposed edges.

Referring to the form of Figures 7 and 8, I illustrate two units, generally indicated as X and Y, and which have bottom walls 2, top walls 3 and appropriate side walls. Where two units are employed the ends are formed to abut against each other, as shown at 100, and any suitable securing means 101 may be employed for securing the two members together. A closure 102 is secured to one end of one unit, and a closure 103, with the appropriate fans 60, is secured to the opposite end of the other unit. As above pointed out, the freezer plate shelves in the two units are formed and positioned to approach each other along the junction 100 to define the fan aligned passages 60a and the passages 60b, which are out of alignment with the fans, and which extend from end to end of the unit.

It will be realized that, whereas, I have described and illustrated a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

The use and operation of the invention are as follows:

It will be understood that the housing proper may be made of any desired length. For example, it may be made and conveniently shipped in lengths as great as ten feet, or possibly somewhat greater. However, it may be advantageous, when greater lengths are desired, to make the housing in a plurality of separable parts. For example, a plurality of the housings shown in Figure 2 may be placed end to end and suitably connected, using only the two doors shown in Figure 2 for the ends of the entire structure so formed. Thus a double unit may be provided, which is open from end to end. As a matter of convenience, I have made the unit shown in the present drawings open from end to end, with the end or door openings of the same cross section as the normal intermediate portion of the unit. Thus by merely removing the intermediate doors, any desired number of units, within reason, may be placed end to end and suitably anchored or locked together, to provide a longer length of travel for the recirculating air. Such a structure is shown in Figure 7.

Note that the interior of the unit shown in Figure 2 is divided into a plurality of passages extending from end to end of the unit, each such passage being defined between or formed by an upper and a lower freezing plate. Some of the passages, which are aligned with the fans, receive the direct blast of air from the fans. The inter-

shelf or inter-plate passages which are not aligned with the fans serve as return ducts for recirculating the air delivered by the fans. The result is that during the use of the device, and when the fans are operating, air is always moving at relatively high speed across all the articles or material positioned on any of the shelves or in any of the passages. It will be understood that in the use of the device a volatile refrigerant is cycled through the plates. In practice, the recirculation of the air, which is cooled by the plates, cools the material or articles being treated for faster than they will cool if merely left on the plates. Thus, although the fans merely circulate or recirculate air which is subjected to the temperature of the freezing plates, nonetheless, the circulation and recirculation of the air greatly increases the freezing speed and shortens the time necessary to reduce the articles or material being treated to the desired low temperature.

The structure herein shown may be used advantageously within a space where the ambient temperature is considerably higher than the temperature within the housing. I therefore find it advantageous to provide a heavily insulated container. Whereas I illustrate, in Figure 2, a housing with a door at each end, it will be understood that the inner end of the unit may, under some circumstances, be permanently closed. However, I find it practical to provide a door at each end of the unit, with blowers preferably mounted on one door only.

It will be understood that where multiple units are employed the evaporator coils of the shelves of the individual units may be connected in any suitable manner to the cycling mechanism. Whereas, in the diagram of Figure 6, I illustrate the shelves of a single unit separated into two groups, it will be understood that the shelves of each unit may form an individual group, the cycling diagram being the same, as shown in Figure 6, except for an increase in the number of plates in each individual group. It will be further understood that any other suitable means or arrangement for connecting the plates to the compressor-condenser unit may be employed.

I claim:

1. In a refrigerating device for freezing materials, a cabinet having walls of insulating material defining an open-ended passage, normally stationary shelves in said passage defining a plurality of parallel inter-shelf ducts, said shelves having end edges spaced inwardly from the ends of the passage, said shelves having evaporator coils for the evaporation of a volatile refrigerant, closures for the ends of the passage, and air circulating means aligned with some of the inter-shelf ducts and out of alignment with others of the inter-shelf ducts, said latter ducts constituting return passages for the circulated air.

2. The structure of claim 1 characterized in that the air circulating means includes an air circulating fan mounted on the closure for one end of the passage.

3. The structure of claim 1 characterized in that the air circulating means includes a plurality of fans mounted on the closure for one end of the passage.

4. In a refrigerating device for freezing materials, a plurality of cabinet units, each such unit having walls of insulating material defining an open-ended passage, means for securing together two opposed open ends of a plurality of

such units, closures for the ends of the open-ended passage thus formed, normally stationary shelves in said passage defining a plurality of parallel inter-shelf ducts, and air circulating means aligned with some of the inter-shelf ducts and out of alignment with others of the inter-shelf ducts, said shelves having evaporator coils for the evaporation of a volatile refrigerant.

5. The structure of claim 4 characterized in that freezer shelves are located in both units, the individual freezer shelves in each unit being aligned with and terminating adjacent corresponding shelves in the other unit.

10 HERMAN W. KLEIST.
